SLIDE PLATE TYPE VOLUME CONTROL VALVE

Richard C. Hare, Wauwatosa, Wis., assignor to Dynex, Inc., Pewaukee, Wis., a corporation of Wisconsin
Filed Sept. 8, 1958, Ser. No. 759,477
1 Claim. (Cl. 137—625.25)

This invention relates generally to hydraulic mechanisms and in particular to pressure fluid control valves of the slide plate type for controlling the volume of pressure fluid flow which is being delivered to a source of utilization from several sources of pressure fluid supply.

It is an object of the present invention to provide a volume control valve for selectively directing the flow of pressure fluid which is being delivered from several sources to a common load or source of utilization. The invention further contemplates the use of such a valve with a multi-piston pump having separate discharge conduits.

The invention provides a valve of the above type which is economical to manufacture and efficient in performing its intended functions.

These and other objects and advantages will appear later as this disclosure progresses, reference being had to the accompanying drawings, in which;

FIGURE 1 is a side view of a valve made in accordance with the present invention;

FIGURE 2 is a plan view of the valve shown in FIGURE 1;

FIGURE 3 is a perspective view of the slide plate used in the valve shown in FIGURE 1;

FIGURE 4 is an axial sectional view of a hydraulic pump with which the present invention finds particular utility; and

FIGURE 5 is a schematic view of the pump shown in FIGURE 4 when used with the valve of the present invention.

Referring in greater detail to the drawings, the valve 9 made in accordance with the present invention is of the slide plate type and includes three plate members 10, 11 and 12 which are suitably finished and secured together by any suitable means, such as cap bolts (not shown) to thereby form a valve body. The central plate member 11 has a large rectangular opening 14 formed in its central portion which defines a valve chamber in this valve body. End plate 10 contains the cylinder port C, tank port T and pressure port P2. End plate 12 contains the pressure ports P1 and P3. As best shown in FIGURE 1, all of these ports are in communication with the valve chamber and terminate therein in spaced apart axial alignment. The tank port is located at one side of the pressure inlet ports and the load port C is located at the opposite side of the inlet ports.

A slide plate 16 is reciprocable in the chamber and is finished to provide a slideable sealing fit therein. The plate 16 is secured to a control rod 17 through which it is shifted by any suitable means (not shown). Plate 16 has two elongated and aligned ports or slots 20 and 21 extending therethrough which are selectively registerable with the porting in the plate members 10 and 12, as will appear more fully hereinafter.

In FIGURE 4 there is shown a hydraulic pump 22 with which the present invention finds particular utility. Such a pump is fully described in the co-pending U.S. application of David T. Blair, Serial No. 661334, filed May 24, 1957, now Patent No. 2,941,475, issued June 21, 1960, entitled "Hydraulic Pump," and assigned to the assignee of the present application. It is thought sufficient to say, for purposes of this disclosure, that the pump has a plurality of pumping chambers 24 in which the pistons 25 are reciprocated by the rotatable wobble plate 26 to effect suction strokes when the pistons are

2

moved to the left (as viewed in FIG. 4) and pumping strokes when they are forced to the right. In the illustration chosen for purposes of this disclosure, the pump has six pumping chambers which are adapted to be in communication, via outlet check valves 27 and cross bores 28, with a common discharge outlet 29. Alternatively, the discharge from each of the pumping chambers may be made to pass independently from the pump via an isolating valve assembly 30, instead of to the common port 29 as when the regular valve plug assembly 31 is used.

When four of these isolating valves 30 are used, as best shown in FIGURE 5, the discharge from the remaining two chambers is discharged through the conduit 32 that is connected to the common discharge port 29. The isolating valves are paired up to the conduits 33 and 34 so as to give three separate flows of pressure fluid.

In certain hydraulic circuits it may be desirable to selectively direct part or all of the pump discharge to a common source of utilization. In other words, it may be desirable to direct the discharge from some of the chambers to the work and the discharge from the remaining chambers to the tank, or elsewhere.

The volume control valve 9 provided by the present invention permits a fixed displacement pump of the above type to furnish pressure fluid as does a variable volume pump. The pressure fluid is furnished in steps or graduations, that is, in the example shown, in multiples of two pumping chambers.

As the invention has been shown, the three separate lines of fluid pressure 32, 33 and 34 are in communication with the pressure ports P2, P1 and P3, respectively, of the valve. Figure 5 shows the slide plate 16 positioned to direct the discharge of all three conduits 32, 33 and 34 to the load via slot 21 and conduit C. In this position the conduit T leading to the tank or elsewhere is blocked, and the entire pump output is used to perform work.

By progressively moving the plate 16 to the left, the conduits 33, 32 and 34 may in that order be made to discharge via slot 20 into the conduit T rather than into the conduit C. When the plate is moved to the extreme left position, all of the flow will be dumped to the tank via slot 20 and conduit T, and the conduit C will be blocked.

Detents 36 to 39 are formed in the plates 10 and 12 and the spring loaded balls 40 in the aperture 41 of the slide plate selectively engaged these detents when, respectively, the plate is positioned to deliver all the fluid, fluid from conduits 32 and 34, fluid from only conduit 34, and none of the fluid, to the conduit C. Thus the plate is positively located in any one of its flow directing steps.

By having two separate porting slots 20 and 21, as shown, the pump flow may be directed entirely or partially to either the load or the tank; or a portion of the entire flow may simultaneously be directed to both the work and tank.

While the illustration chosen for purposes of this disclosure shows a six-cylinder pump with suitable conduits to provide three discharge pressure lines communicating with a valve having three pressure inlets, a pump having any number of separate pumping chambers may be utilized and the flow therefrom divided into various numbers of conduits for communication with a valve having a corresponding number of pressure inlets.

The slide plate type valve made in accordance with the present invention is simple in design and its particular porting arrangement in the various plates which comprise the valve make it economical to manufacture and result in an efficient valve having minimum leakage problems.

Various modes of carrying out the invention are con-

templated as being within the scope of the following claims particularly pointing out and distinctly claiming the subject matter which is regarded as the invention.

I claim:

A hydraulic fluid volume control valve comprising, a central plate having a rectangular opening therethrough, a side plate sealingly secured to each of opposite sides of said central plate to thereby define a valve body having a chamber therein, a series of fluid pressure inlet ports extending through said body and communicating with said chamber in alignment with one another, a load port extending through said body from said chamber at one side of said inlet ports, a tank port extending through said body from said chamber at the other side of said inlet ports, and a slide plate sealingly reciprocable within said chamber and having a pair of elongated porting slots therethrough which are in alignment with one another in respect to the direction of slide plate reciprocation, the arrangement being such that when said slide plate is at one limit of its travel one of said slots registers with all of said inlet ports and with said load port, and when said

slide plate is at the other limit of its travel the other of said slots places said tank port in registration with all of said inlet ports.
